APPARATUS FOR AND THE COOLING OF ANNEALED GOODS IN COOLED VESSELS

Application filed October 25, 1929, Serial No. 402,445, and in Germany March 22, 1928.

An application has been filed in Germany March 22, 1928.

Commencing with the supposition that it is known that in the ordinary annealing process oxidation of the material takes place after its removal from the furnace a treatment and a device are hereinafter explained with the aid of which by the exclusion of the atmospheric air after annealing scaling of 10 the material is prevented.

Fig. 1 represents a sectional view of my apparatus.

Fig. 2 shows a modification of the apparatus in Fig. 1 and is also in section.

15 To this end the material heated in the annealing furnace to its maximum temperature (represented in Fig. 1 of the accompanying drawing as an annealing box *a* containing cold rolled strip iron heated from 6-700° C.) is inserted in the cylindrical receptacle *b*. This receptacle *b* is situated in a further receptacle *c* which is filled with a slowly combustible liquid *d* (oil). In order to avoid boiling of this liquid quantity employed as 20 packing medium a water-cooled pipe coil *e* is arranged to surround the receptacle *b*. For the purpose, moreover, of preventing the receptacle *b* from floating in the liquid referred to it is weighted by a counter weight *f*. 25 If now after the airing cock *h* has been closed a sheet metal bell *g* indicated by hatched lines is introduced into the receptacle *c*, the charge *a* is thereby subjected to a hermetic closure. The air still contained in the bell

30 *g* which would have access to the heated material and accordingly cause oxidation is rendered harmless by the addition to the charge shortly prior to the placing of the bell *g* of a suitable readily combustible substance (for example petroleum) which after 35 the insertion of the bell *g* extracts the noxious oxygen from the closed space by subsequent combustion.

Consequently in the closed space a gas mixture is generated which as regards the

charge exhibits a neutral behaviour. The bell *g* due to its own weight and reduction of space as a result of the combustion process will be caused to sink in the packing liquid *d* down to a certain extent. Conjointly with this the gas mixture formed will be heated by the charge *a* resulting in an expansion of the gases whereby the bell *g* is forced to rise. Now at the lower edge of the bell *g* there are four openings *i* which in the rising movement of the bell *g* reach the liquid level providing a regulated exit for the expanding gases. The result is that the bell *g* will always tip with its lower edge in the liquid being balanced without lateral sway. When 50 the expansion of the gas mixture is terminated so that the heating has reached its maximum a fall of pressure and consequential reduction of space will gradually set in in the interior by the cooling of the charge 55 *a* and the bell *g* will sink. The dimensions of the bell are dependent on the volume and charging temperature of the charge *a* so that after the cooling of the gas mixture a floating 60 of the bell *g* is rendered possible in the low 65 position. When this position is attained the airing cock *h* is opened in order to prevent the liquid column *d* between the bell *g* and the receptacle *b* from being drawn up and the bell *g* can be removed and consequently 70 75 the charge be taken from the receptacle.

Another manner of application of the arrangement described shall hereinafter be explained.

After the cock *h* is opened and a gas generating substance has been added to the charge *a* (for example gas coal) which readily ignites, the bell *g* is placed in position. Combustion takes place of the oxygen contained in the receptacle and the bell *g* sinks to 80 its low position resting with its bottom on the edge of the receptacle *b*.

The cock *h* is now closed and after the oxygen in the interior is bound up gasification 85 sets in of the incompletely burnt gas driv- 90

ing medium resulting in a rise of the bell *g*. The neutral gas formed in the raised bell *g* is further heated by the charge *a* until an outflow takes place in the highest position of 5 the bell *g* by way of the ports *i*. The cooling setting in thereafter results as already mentioned in the preceding process in a descent of the bell *g* until the cooling is effected. The charge *a* may then be removed as already described after the cock *h* has been opened and the bell *g* taken off.

According to Fig. 2 a receptacle *b* instead of being surrounded with a cooling coil *e* may be equipped with a cooling jacket *k* 15 adapted to separate the wall of the receptacle *b* circumferentially completely from the packing liquid *d* preventing the latter therefore from becoming excessively heated.

Arranged within the jacket is by preference a cylindrical partition *l* which is closed at the bottom and open at the top *m*. By this partition the jacket is divided into an outer and an inner cylindrical portion. Arranged in the outer portion moreover are helical 25 guide vanes *n*. By these guides the gaseous or liquid cooling medium admitted by way of the conduit *o* is caused to flow along the helical path upwardly in the outer portion of the jacket and then at the upper edge through 30 the openings *m* to the inner portion of the jacket downwardly leaving at the lower end by way of a socket *p*. The gaseous or liquid cooling medium prevents the heat emanating from the charge *a* from excessively heating 35 the packing liquid *d* since it forms circumferentially a complete separation between the charge and the liquid.

I claim:

1. Process for cooling heat-treated material which consists in placing the material while in highly heated condition in a receptacle enclosed within a double-walled vessel, the space between the walls of which is filled with a liquid of high boiling point, inverting 45 an open-ended vessel over said receptacle, the open end of said vessel being immersed in the liquid thereby to form a seal, adding to the heat-treated material a combustible fuel thereby to neutralize any air within the inverted vessel and cause said vessel to move upward to permit escape of excess gas, allowing said inverted vessel to sink in said liquid in proportion to the gradual equalization of the temperature within and without the material-containing receptacle until the open end of the inverted vessel reaches the bottom of the cooling receptacle, and opening the inverted vessel to atmospheric communication.

2. Process for the cooling of heat-treated material which consists in placing the material while in highly heated condition in a receptacle together with a gas-generating medium, enclosing said receptacle in a double-walled vessel, the space between the walls of 65 which is filled with a liquid having a high

boiling point, inverting an open-ended vessel over the heat-treated material and immersing the open end of said vessel in said liquid thereby to form a hermetic seal, establishing atmospheric communication with the interior of the vessel above said liquid to allow the vessel to sink by gravity into the liquid until the open end of said vessel reaches the bottom of the material-containing receptacle, discontinuing said atmospheric communications thereby to cause consumption of the oxygen of the inclosed air by the combustion of the gas-generating medium and causing the vessel to be raised by the unburned products of the gas-generating medium and the heating of the neutral gas so as to permit escape of excess gas, and finally permitting the vessel to drop in accordance with the cooling off of the heat-treated material, and after the complete cooling of the material again establishing atmospheric communication with the interior of the vessel thereby to permit ready removal thereof.

3. Apparatus for cooling annealed material, comprising a container having a plurality of concentrically disposed spaced-apart walls, a vessel disposed centrally of said container for receiving the material to be cooled, the space between two of the walls of said container being filled with a slowly combustible liquid, and a vertically movable bell having its open end immersed in said liquid thereby to form a liquid seal for said vessel, said bell being of a height approximately equal to that of the liquid container whereby the bell will be free to rise and fall within the liquid container in response to the pressure and expansion of the gases therein while maintaining said liquid seal throughout said movement, said bell being provided with perforations in its wall adjacent to its lower end thereby to cause escape of said gases when the bell has risen sufficiently to carry said perforations above the level of the liquid in the container.

4. Apparatus for cooling annealed material, comprising a triple-walled container having its walls spaced apart thereby to form between them a pair of concentric annular spaces, a vessel disposed centrally of said container for receiving the material to be cooled, the space between the outermost wall and the center wall of the container being filled with a slowly combustible liquid, a cylindrical partition disposed approximately midway between said center wall and the innermost wall of the container, said partition being of slightly less height than the walls of the container thereby to divide the space between said walls into a pair of annular spaces communicating at their upper end, a conduit communicating with the lower end of the outer one of said annular spaces, means disposed in said outer annular space for directing a cooling medium from said conduit up

ward and into the inner annular space, and a vertically movable bell having its open end immersed in said liquid thereby to form a liquid seal for said vessel, said bell being of a height approximately equal to that of the liquid container whereby the bell will be free to rise and fall within the liquid container in response to the pressure of the gases therein, while maintaining said liquid seal through-

10 out said movement.

In testimony whereof I have signed my name to this specification.

HERMANN PRÜFERT.
